pany, Chicago, Ill., a corporation of Indiana

Application December 15, 1941, Serial No. 422,984

4 Claims. (Cl. 260—683.5)

This invention relates to an improved process for the isomerization of low-boiling paraffinic hydrocarbons by means of an aluminum halide catalyst activated by a hydrogen halide. This application is a continuation-in-part of our co-pending application No. 245,570 which issued as Patent No. 2,266,012 on December 16, 1941.

An object of our invention is to provide an improved system for the efficient and more complete conversion of paraffinic hydrocarbons to isomers of higher octane number. Another object of our invention is to provide an improved method for the introduction of catalyst into a conversion zone. A further object of our invention is to provide improved methods for effecting intimate contact between catalyst, light paraffinic hydrocarbons, activator and hydrogen in a reaction zone. A still further object of our invention is to provide a method for obtaining the greatest possible yield of isoparaffinic hydrocarbons per unit of catalyst consumed in an isomerization process. Other objects and advantages will become apparent as the detailed description of our invention proceeds.

When our invention is applied to refinery naphtha we find it desirable to first fractionate the naphthas in order to remove undesirable components; for the isomerization of a charging stock consisting essentially of hydrocarbons having five and six carbon atoms per molecule, it is desirable to remove substantially all of the heptanes and to have relatively low concentrations of aromatics and the naphthenes.

The feed stock for our isomerization process can be any substantially saturated naphtha rich in straight-chain paraffinic hydrocarbons; for example it can be a relatively pure normally liquid straight-chain or slightly branched-chain paraffin hydrocarbon, such as normal pentane, normal hexane, 2 methyl pentane, etc., but generally, predominantly straight-run naphthas such as those from Michigan, Pennsylvania and Mid-Continent crude oils are preferable, since they are much more readily available. Another excellent feed stock is a highly paraffinic naphtha produced by the Fischer-Tropsch process from carbon monoxide and hydrogen. Natural gasoline fractions and so-called distillates are also suitable and are plentiful and inexpensive in some production areas. The feed stocks are preferably in the butane to hexane boiling range and they may have end points (or 95% points) as high as 170 to 180° F. although lower 95% points are preferred. They preferably contain less than about 5% and preferably 0.5 to 2.0% or less of

aromatic hydrocarbons. In many cases a preliminary solvent extraction step or other treatment is necessary or desirable in order to reduce the aromatic content. Olefinic hydrocarbons are also undesirable and should not be present in more than very small amounts, while cycloparaffins or naphthenic hydrocarbons can be tolerated in considerable quantities. It is also frequently desirable to limit or eliminate paraffinic hydrocarbons higher boiling than the hexanes. The heptane content should not exceed 10% and should preferably be less than 5%. The feed stocks should preferably contain at least 50% of paraffin hydrocarbons and those containing at least 80% of paraffin hydrocarbons are especially desirable. At least a substantial part of the charging stock is employed for absorbing hydrogen chloride from gases produced in the system.

The aluminum chloride catalyst is preferably introduced as a solution in a hydrocarbon stock, and most desirably in a butane fraction. It is possible however to employ a light naphtha cut containing a substantial amount of butane as the solvent, or even to use the C₅—C₆ fraction for this purpose. The part of the charge containing the hydrogen chloride is passed through a heat exchanger after the absorption step and then introduced into a reactor. The part of the charge used for dissolving make-up aluminum chloride is heated prior to the solution step in order that the desired amount of solution may be effected. Hydrogen should be added to the reactor in the case of C₅—C₆ charging stocks. The reactor is operated at a temperature within the approximate range of from 100° F. to 400° F., preferably 200° F. to 300° F., and at a pressure within the approximate range of about 100 to about 3000 pounds per square inch, preferably about 500 to about 1500 pounds per square inch. For a C₅—C₆ fraction we have found that excellent results are obtainable at a temperature within the approximate vicinity of 250° F. and a pressure within the approximate vicinity of about 850 to 900 pounds per square inch.

The amount of hydrogen required will vary somewhat with temperature, pressure and hydrogen chloride concentration in the reaction zone, ranging from about 20 cubic feet per barrel of stock charged at low temperatures, low pressures and low hydrogen chloride concentrations to 200 or more cubic feet per barrel at high temperatures, pressures and high hydrogen chloride concentrations. For optimum conditions in the operation on a pentane-hexane hydrocarbon fraction, the actual hydrogen consumption will be

about 100 cubic feet per barrel and in order to insure the presence of the requisite amount of hydrogen in the reactor we prefer to introduce from about 100 to about 300, preferably about 200 cubic feet of hydrogen per barrel of charging stock.

The amount of make-up aluminum chloride may be within the approximate range of 0.1 to 4.0 pounds per barrel of total charging stock, usually within the general vicinity of 1 pound per barrel. An important feature of our invention is the introduction of this make-up aluminum chloride to the reaction zone in the form of a solution in a light hydrocarbon, which hydrocarbon may be a portion of the original feed stock, but more desirably is a fraction rich in butane.

The amount of hydrogen chloride may be within the approximate range of about 5 to about 30 pounds of hydrogen chloride per barrel of total stock charged, usually within the general vicinity of about 10 pounds per barrel, but since only a small portion of the hydrogen chloride is actually consumed, the major portion of it may be recovered and reintroduced as will be hereinafter described.

While the materials introduced into the reactor with the charging stock are aluminum chloride, hydrogen chloride, and hydrogen, the effective catalyst in the reactor is an aluminum chloride-hydrocarbon complex which may contain more or less dissolved or uncombined aluminum chloride. At the beginning of an operation we prefer to have the reaction towers at least about half full of this complex although the complex can be formed in situ by the combination of hydrocarbons with aluminum chloride in the presence of hydrogen chloride. The fresh complex is relatively non-viscous and has a specific gravity about twice as great as that of the charging stock, so that when charging stock is introduced at the base of the reactor it flows as a dispersed phase upwardly through the complex, thus effecting intimate contact between the charging stock and the complex. The incoming charging stock is mainly in the liquid phase but it may be partially vaporized by the gaseous hydrogen, about half of the volume of the upflowing stream being gaseous because of the introduced hydrogen which serves the function of promoting turbulence and effecting intimate mixing of charging stock and complex. Based on the stock charged and the total amount of complex in the reactor, the space velocity should be within the approximate range of 0.2 to 4 volumes of liquid feed per hour per volume of complex in the reactor, preferably about $\frac{1}{2}$ to 2 volumes per hour per volume of complex.

In the upper part of the reactor sufficient settling space is provided to permit separation of complex from the clear reaction product. To insure adequate settling we can either increase the cross-sectional area of the upper part of the reactor or provide a separate chamber of large, horizontal, cross-sectional area. This enlarged upper section or separate chamber has two important functions: (1) It provides a soaking drum wherein dissolved catalyst can effect further isomerization of the substantially clear product for obtaining a more desirable product distribution, and (2) it provides a large cross-sectional area for substantially complete separation of any entrained complex so that the complex can be returned to the reactor before the products enter the cooler. The settled com-

plex is returned to the reactor or to a separate recovery system and the clear products are passed through a cooler to a low-pressure settling chamber for the release of hydrogen chloride and dissolved catalyst.

At room temperature and atmospheric pressure only about 0.10 gram of aluminum chloride can be dissolved in a liter of light naphtha (or isomerization product) of the type described. Under the reaction temperature and pressure about 50 to 75 times as much aluminum chloride may be held in solution. It is essential that dissolved catalyst material, whether aluminum chloride or complex, be removed from the products before they enter the fractionation system, not only because of catalyst losses which would otherwise be suffered but because of the complications and expense that would be encountered in handling a product containing such dissolved catalyst material. The gases containing hydrogen chloride can be scrubbed by a portion of the charging stock for recovering the hydrogen chloride and the substantially catalyst-free product can be charged to a hydrogen chloride stripper and sent to a fractionation system.

We have found that a considerable amount of hydrogen chloride can be recovered from the product in a simple stripping column which is operated at a pressure of about 200 pounds per square inch, a top temperature in the approximate range of 100° F. to 150° F. and a bottom temperature in the approximate range of 300° F. to 400° F. The final products are neutralized with caustic, water washed and, if necessary or desirable, they can be fractionated or stabilized.

We can employ a multi-stage reaction with complex, the first stage being with relatively spent complex at relatively high temperature, and the second step with relatively fresh complex at a lower temperature. Complex from the low temperature stage can be transferred to the high temperature stage. Substantially constant complex activity can be maintained in each zone by the addition of active materials thereto and the withdrawal of relatively spent catalyst therefrom. Hydrogen chloride can be recovered from the spent catalyst by treatment with water or sulfuric acid.

The invention will be more fully understood from the following detailed description of a specific example thereof read in connection with the accompanying drawing which forms a part of this specification and which is a diagrammatic flow sheet of one embodiment of our improved process.

Referring to this drawing, about 5000 barrels per day of light naphtha is charged by pump 10 through line 11 and heat exchanger 12 to an intermediate point in light naphtha fractionator 13 which can be about 4½ feet in diameter by about 50 to 55 feet high. This fractionator is provided with conventional heating means 14 at its base, and is operated under such conditions that heptane and heavier hydrocarbons are withdrawn from the base of the column through line 15. Where a close fractionation is desired between butanes and heavier hydrocarbons or between hexanes and lighter hydrocarbons a plurality of fractionating columns will of course be employed but in the accompanying drawing such a fractionation is diagrammatically illustrated by a side stream draw-off on fractionating column 13. Such a side stream draw-off may of course be actually used where close frac-

tionation is not essential and where, as in this case, it may simply be desirable to withdraw one stream which is chiefly C_5 and C_6 hydrocarbons and another stream which is chiefly butanes and perhaps pentanes. The butanes and perhaps pentanes are taken overhead through line 16 and cooler 17 to reflux drum 18. A portion of the reflux condensate is returned by pump 19 through line 20 to the top of fractionator 13 to serve as reflux. Reflux condensate may, if desired, be withdrawn from the system through line 21 and valved line 22, while the lighter gases are vented overhead. The pentanes and hexanes can be withdrawn as a side stream by pump 23 through cooler 24 and line 25, and about 50% to about 100% of this stream introduced through line 26 to the top of absorber 21. Any charging stock not sent to the absorber can be directed to the solution tank by pump 28 and line 29.

The hydrogen chloride required for the reaction is absorbed in the major portion of the feed stock, preferably the higher boiling portion thereof, before it is heated or introduced into the reactor. The hydrogen chloride absorber can be about one and one-half feet in diameter by twenty-eight feet high and it can operate at a pressure of from about 100 to about 300, for example about 250 pounds per square inch. A stream of hydrogen chloride gases from the system is introduced at the base of this absorber through line 31. Make-up hydrogen chloride can be introduced through line 32. Instead of make-up hydrogen chloride we can employ chlorine, an alkyl chloride, or other substance which will supply the necessary hydrogen halide activator under reaction conditions. We prefer, however, to employ hydrogen chloride and to generate it, if necessary, in a separate generator.

The hydrogen chloride generator 33 can be of any known type. The chlorine supplying agent introduced through line 34 is preferably chlorine gas although it may be sodium chloride, 22° muriatic (hydrochloric) acid or other halogen-containing agent. The hydrogen-supplying agent introduced through line 35 can be hydrogen gas, a hydrocarbon, sulfuric acid, etc. Thus hydrogen and chlorine can be burned in generator 33 to supply hydrogen chloride. Wax tailings or other hydrocarbons can be introduced through line 35 and chlorinated by chlorine gas introduced by line 34 to produce hydrogen chloride and chlorinated hydrocarbons. (Additional hydrogen chloride can of course be obtained from the latter.) Sodium chloride or hydrochloric acid can be introduced through line 34 and sulfuric acid through line 35, but in our system this hydrogen chloride generator can operate under such pressure that no compressors are required for introducing the hydrogen chloride through line 36 to the base of absorber 21, and this hydrogen chloride does not require the purification which is generally necessary even for the production of commercial grades of hydrochloric acid. By-products from the hydrogen chloride generator are withdrawn through line 37.

The hydrogen chloride picked up in absorber 21 should be sufficient to give an amount of hydrogen chloride in the total stock entering the reactors within the approximate range of 2% to 10%; that is, in the general vicinity of 5% by weight based on total stock charged. Two-thirds or more of this hydrogen chloride can be obtained by gases from line 31. Unabsorbed gases such as

small amounts of hydrogen, methane, etc. are purged from the system through line 38, thus eliminating not only gaseous impurities from line 31 but also gaseous impurities from line 36.

It is a special feature of this invention that the fresh aluminum chloride be introduced into the system in solution in a light hydrocarbon stock. At room temperature and pressure, the solubility of aluminum chloride in ordinary naphtha is negligible and only about 0.1 gram of aluminum chloride can be dissolved in a liter of the C_5 — C_6 hydrocarbons. Under the reaction temperatures and pressures, however, about 50 to 75 times as much aluminum chloride can be held in solution in the C_5 — C_6 hydrocarbons. Aluminum chloride has been found to be much more soluble in butanes, and particularly in normal butane, so that in a preferred embodiment of our invention we prefer to dissolve the aluminum chloride in a butane stream and to add the butane with its dissolved catalyst to the light naphtha stream going to the reactors in order to supply make-up aluminum chloride. For example, at about 250° F. approximately 5.5% by weight of aluminum chloride will be dissolved in normal butane. Moreover, the presence of normal butane in the isomerization system is not at all detrimental and in the upper range of temperatures employed therein is beneficial, due to the fact that it represses the formation of any additional amounts of normally gaseous hydrocarbons of this type. In addition, at least a part of the normal butane will undergo isomerization to isobutane—a product valuable in itself for the synthesis of various high octane number fuels and for blending with gasolines of low volatility in limited amounts. Accordingly, butane or a fraction rich in butane, from reflux drum 18 may be pumped by pump 39 through line 40 and heater 41 to aluminum chloride solution tank 42 at a temperature of about 250° F. or thereabouts. This hot stream dissolves sufficient aluminum chloride to supply all of the necessary make-up aluminum chloride to the system. Fresh aluminum chloride is added from source 43 to aluminum chloride solution tank 42 and the aluminum chloride may be present in the tank in the form of lump or powdered anhydrous aluminum chloride and may be distributed throughout the tower or maintained in beds or by other similar means. Sufficient pressure will of course be required to maintain the butane fraction in liquid state and the pressure may be high enough to introduce the solution into the reaction zone. The solution tank is diagrammatically illustrated in the drawing and in actual practice may consist of one or more upflow chambers wherein aluminum chloride lumps are retained on a suitable screen support, the butane stream entering the tank at the bottom and leaving at the top. One of such solution tanks may be charged with aluminum chloride at atmospheric pressure while another of such tanks is on stream.

The amount of aluminum chloride that is dissolved in the solution tank is primarily dependent upon the temperature and the nature and amount of the butane stream. By simply controlling flow rates (pump 39) and temperature (heat exchanger 41) we may closely control the amount of make-up aluminum chloride which is thus charged to the system. The amount of this stream will usually be less than 50% of the total charging stock and for example may constitute about 10 to 30% of said charging stock. The temper-

ature will usually be within the range of about 100 to 400° F. or more, for example, about 200 to 300° F.

The hydrogen chloride-rich charging stock from the base of absorber 27 is pumped by pump 44 through heater 45 and lines 46 and 47 to the base of the first reactor 48 at a pressure within the approximate range of 500 to 1500 pounds per square inch, for example, about 850 or 900 pounds per square inch. Hydrogen from source 49 (or from other sources that will hereinafter be described) is introduced by compressor 50 and line 51 into line 46 in amounts within an approximate range of 100 to 300, for example about 200 cubic feet per barrel of stock charged to the reactor (the hydrogen being measured at 60° F. and atmospheric pressure). The aluminum chloride solution from aluminum chloride solution tank 42 is introduced through line 52 (and pump 53 if further pressuring is required) into the reactor 20 and the amount of aluminum chloride in solution in the butane may be about .1 or 1 pound per gallon. Based on the total charging stock introduced into the reactor, the amount of aluminum chloride introduced through line 52 is within the approximate range of 0.1 to 4 pounds, preferably about 1 pound per barrel of charging stock. The stream entering reactor 48 through line 47 may be at a temperature within the approximate range of 200° F. to 300° F., for example about 250° F.

Reactor 48 may be a vertical tower about 5 or 6 feet in diameter by about 18 or 20 feet long. When the reaction is initiated this reactor can be about half filled with an aluminum chloride-hydrocarbon complex, the density of which is within the approximate range of 1.2 to 1.7, and which can be maintained during the reaction within the general vicinity of 1.5 by methods hereinafter described. The density of the light hydrocarbon charging stock is less than half that of the complex. The charging stock is chiefly in the liquid phase but some of it will be vaporized by the upflowing gases which constitute about one-half the volume of the upflowing stream and which produce turbulence and intimate mixing in the reaction zone. The space velocity should generally be within the approximate range of 0.2 to 4 volumes of liquid charging stock per hour per volume of complex in the reactor and under preferred operating conditions within a single reactor it should be within the general vicinity of one-half volume of liquid charging stock per hour per volume of catalyst complex in the reactor. Higher space velocity may, of course, be employed in this reactor, particularly where a plurality of reactors are employed in series.

Complex settles from the upflowing reaction products in the top of the tower, and if desired the tower top can be enlarged to provide increased settling area. We prefer, however, to withdraw the reaction products in the tower top through lines 54 and 55 to a soaking drum or warm settling chamber 56 which can be a horizontal or slightly inclined drum about 3 feet in diameter by about 10 feet long. We have discovered that there is a large amount of dissolved catalyst in the product at this point and this dissolved catalyst in the soaking drum may have a beneficial effect on distribution of products. In other words, the isomerization equilibrium in drum 56 is not the same as in reactor 48 and this supplemental contact with dissolved catalyst in drum 56 may contribute to additional formation

of desired isomerization products. The complex carried into the soaking zone is as fluid as freshly prepared complex, i. e., it may be quite different in its properties than the average complex in the initial reactor.

Drum 56 also serves the important function of removing any undissolved complex, separated complex being withdrawn from the base of the drum through line 57 and returned without necessity of pumping. Complex removed at this point helps to prevent fouling of the heat exchanger when clear products are withdrawn through line 58, cooler (heat exchanger) 59, and pressure reduction valve 60 to the cool settling drum 61 which is maintained at a temperature of about 100° F. or less and at a pressure within the approximate range of 100 to 300, for example about 250 pounds per square inch. The cool settler may be a horizontal or slightly inclined drum about 5 or 6 feet in diameter and about 16 feet in length. Released gases leave the top of the cool settler 61 through line 62 which discharges into line 31. The reduced pressure and cooling effects a considerable precipitation of catalyst material in the cooled settler and the precipitated catalyst material is withdrawn from the base of this settler by means of pump 63 in line 64.

The clear product, which is now substantially free from catalyst and which contains a decreased amount of hydrogen chloride, is withdrawn through line 65 and introduced by pump 66 into hydrogen chloride stripping tower 67 which can be a column about 3 feet in diameter and about 33 feet in height. This stripping column can be provided with heating means 68 at its base and it can be operated at a pressure of about 200 pounds per square inch with a top temperature within the approximate range of 100° F. to 150° F. and a bottom temperature within the approximate range of 300° F. to 400° F. The removed hydrogen chloride together with the released gases, such as hydrogen, methane, etc., is taken overhead through line 69 to line 31.

The liquid from the base of the stripper is introduced at a low point in scrubbing tower 70 either directly through line 71 or through a cooler 72. Scrubber 70 may be a tower about 4 feet in diameter, about 32 feet in height, and it can be provided with suitable baffles, trays or bubble plates for effecting intimate contact of the upflowing product with a concentrated caustic solution introduced through line 73. The upflowing neutralized products are washed free from caustic in the upper part of the tower by water introduced through line 74. Spent caustic solution is withdrawn from the base of the scrubber through line 75. The wash water can be withdrawn from a trapout plate (not shown) above the point of caustic inlet, if desired.

The water-washed product can be withdrawn as such, or it can pass from the top of scrubber 70 through line 76 and heat exchanger 77 to an intermediate point in stabilizer 78. This stabilizer is provided with conventional heating means 79 at its base. Butanes and any lighter products can be taken overhead through line 80 through cooler-condenser 81 to reflux drum 82 from which gases can be vented through line 83. Condensed reflux can be returned by pump 84 through line 85 to the top of stabilizer 78. A stream consisting chiefly of butanes can be withdrawn from the system through lines 86 and 87. It can also be recycled via line 88 to solu-

tion tank 42 to supplement or supplant the butane from line 21 for making up the catalyst solution.

If desired, a single "isomate" fraction can be withdrawn from the base of the stabilizer through heat exchanger 77 and line 89. We can, however, withdraw only the heaviest isomate at this point and we can withdraw a light isomate as a separate fraction diagrammatically illustrated as a side stream through line 80. The isomate can be fractionated to insure the removal of any heptanes or heavier products which may be formed and to obtain a product of desired Reid vapor pressure for blending in desired amounts with isooctane to make a super aviation fuel. A representative analysis of isomate produced in this system may be approximately as follows:

	Per cent by volume
Isobutane	2
Isopentane	31
n-Pentane	5
Cyclopentane	3
2-methylpentane	18
3-methylpentane	8
2,2-dimethylbutane	20
2,3-dimethylbutane	2
n-Hexane and heavier	11

If neohexane is a desired end product, it can be separately fractionated and the other isohexanes can be recycled for the production of a further amount of neohexane.

Returning to the reaction system, we can employ a second reactor 91 of similar design to the first reactor 48. Products from the first reactor instead of going to the warm settler through line 55 can pass through line 92 and heat exchanger 93 into the base of this second reactor 91. The operating conditions in the second reactor can be substantially the same as in the first reactor, although we prefer to operate the second reactor at a lower temperature than the first reactor. Thus with the first reactor at 300° F. or more, the second reactor can be at about 250° F. Products from the top of the second reactor pass through line 94 to soaking drum or warm settler 56 as hereinbefore described.

Instead of operating the reactors in series they may be operated in parallel by passing only a part of the charging stock through line 47 to the first reactor and by passing the remainder of the charging stock through line 95 to the base of the second reactor. By means of this arrangement one reactor can be on stream while another reactor is standing by for repair or replacement of catalyst complex.

In general the complex becomes more viscous with age and up to a certain point the catalyst becomes more active with increasing viscosity. These characteristics are apparently determined to a certain extent by the hydrocarbon content of the complex. Fresh complex may contain up to about 37% hydrocarbon but when complex is made in situ in the presence of a large amount of aluminum chloride, and after the catalyst has been used for a period of time it may contain only 10 or 15% hydrocarbons, the balance consisting chiefly of aluminum chloride. We have found the catalytic activity of the complex can be maintained substantially constant by withdrawing a portion of the catalyst from the base of the reactor at about the same rate as an additional amount of aluminum chloride is add-

ed thereto, either in the form of relatively fresh complex or preferably in the form of an aluminum chloride solution. Thus catalyst in the second reactor can be withdrawn through line 86 by means of pump 87 and either introduced through lines 88 and 89 to the first reactor, withdrawn from the system through line 100 or introduced through lines 101 and 102 to hydrogen chloride recovery drum 103. Catalyst from the base of the first reactor can be withdrawn through line 104 by means of pump 105 and introduced through line 106 to the second reactor, withdrawn from the system through line 107 or passed to the hydrogen chloride recovery drum through lines 108 and 102. If the second reactor operates at a lower temperature than the first reactor when in series therewith, we prefer to introduce catalyst from the second reactor through lines 86, 88 and 89 to the first reactor, and to remove catalyst through line 104 in the first reaction to the hydrogen chloride recovery drum 103 or to other recovery systems to be described later. For such operation we prefer to introduce a part of all of the make-up aluminum chloride solution through line 52a to the second reactor.

Settled catalyst complex from the soaking drum or warm settler 56 can be passed from line 57 through lines 110 and 111 to solution tank 42, or through line 112 to the second reactor 91, or through lines 114 and 99 to the first reactor 48. Separated catalyst from cool settler 61 can be passed from line 64 through lines 113 and 111 to solution tank 42, or through line 112 to the second reactor 91 or through lines 114 and 99 to the first reactor 48.

Spent sludge can be discarded from the system but we may either recover a part of the available aluminum chloride therein or introduce it into drum 103 and add to the sludge in this drum through line 115 a sufficient amount of water or sulfuric acid to effect recovery of anhydrous hydrogen chloride. Preferably, the uncombined aluminum chloride is recovered by the method hereinafter to be described, and the remainder of the sludge is then introduced into drum 103 for the production of anhydrous hydrogen chloride. The recovered hydrogen chloride from drum 103 is passed through line 116 to line 31 and absorber 27. The sulfuric acid sludge or cokey residue is withdrawn from drum 103 through line 117. If water is employed, it should be used in less than stoichiometric amounts in order that the recovered hydrogen chloride may be substantially anhydrous. The sludge will thereupon be converted into a cokey mass that can be removed from the drum by hydraulic or other conventional decoking means. A larger amount of anhydrous hydrogen chloride can be recovered by the use of sulfuric acid and the resulting sulfuric acid sludge can be charged to a conventional sludge-coking system for the recovery of sulfuric acid.

Instead of employing relatively pure hydrogen from source 49 we can obtain hydrogen from refinery gases which are rich in hydrogen. Such gases can be introduced through line 120 to absorber 121 which may operate at about 100° F. under a pressure of about 900 pounds per square inch. Absorber oil may be butane from line 21 and line 122. Such oil can be introduced by pump 123 through line 124 to the upper part of the absorber tower 121 for picking up the methane, ethane, ethylene, propane, propylene, etc. in the refinery gases. The unabsorbed hy-

drogen will pass overhead through line 125 to be picked up by compressor 58. The rich absorber oil will pass through line 128 and pressure reducing valve 127 to receiver 128 from which the hydrocarbon gases can be vented to fuel lines or other parts of the refinery through line 129 and the denuded oil can be returned by line 130, pump 123 and line 124 back to the top of the absorber.

As was previously mentioned, a part or all of the uncombined aluminum chloride can be recovered either from the spent catalyst withdrawn through lines 108 and/or 107 and from the catalyst recovered from warm settler 56 and/or cool settler 61. It appears that there is present in the spent catalyst from the reaction varying amounts of free aluminum chloride either in solution in the sludge or held there by occlusion or other physical means, while much of the catalyst precipitated in the settlers is in the form of complex and/or aluminum chloride. The aluminum chloride can be recovered by dissolving it in a quantity of fresh hydrocarbon and after the soluble portion of the catalyst has been removed, the remaining sludge can be withdrawn for the production of hydrogen chloride, as previously described, or for other purposes. Accordingly, the spent sludge from reactors 48 and/or 91 can be directed via valved lines 137 and 138 respectively to line 139 leading to catalyst recovery tank 140. A portion of the butane from line 21 is introduced into recovery tank 140 via valved line 141 and line 142. Means (not shown) are provided for the intimate mixing of the sludge and the butane, preferably at elevated temperatures, such as those set forth for solution tank 42. The butane containing dissolved aluminum chloride is withdrawn from recovery tank 140 via line 143 and augments or supplants a part of the catalyst in line 52 leading to the reactors. The remainder of the sludge is withdrawn via line 144 and can be discarded through valved line 145 or directed to the hydrogen chloride recovery system by opening valve 146 in line 147 which joins line 102.

The catalyst which has settled out in warm settler 56 and/or cool settler 61 can also be directed to a recovery system or returned directly to the reactors, usually in the form of a complex or a slurry in a portion of the product from the settlers. At the temperatures previously disclosed the precipitated catalyst is redissolved in the butane and can be thereupon directed to use in the reaction zones. The recovery tank for the re-solution of aluminum chloride from the settlers can be the same as that used for the recovery of free aluminum chloride from the sludges as shown, or a separate recovery tank (not shown) can be used.

A further alternative procedure is to withdraw butane and light naphtha as a single stream and to direct a portion of this stream through absorber 27 wherein it is saturated with hydrogen chloride and another portion of the stream through heat exchanger 41 to catalyst solution tank 42 wherein a sufficient amount of aluminum chloride is dissolved to supply the necessary make-up aluminum chloride to the system. In this system light naphtha will not be withdrawn as a side stream through line 25 but be included in the overhead from fractionator 13 and recovered from reflux drum 18. The major part of the combined butane and light naphtha stream is directed via pump 19, line 148

5 and line 26 to absorber 27. The minor part of the stream passes through lines 21 and 48 to solution tank 42. When using a stock of this type butane from line 88 is not necessarily recycled.

Another alternative is to use only the light naphtha stream for dissolving the make-up catalyst, eliminating substantially all butane from the system. When employing this process, the butane from reflux drum 18 will be withdrawn through line 22, and only the pentane-hexane stream from line 25 employed. The light naphtha is preferably used at elevated temperatures for making up the solution and temperatures within the range from about 100° F. to 400° F., preferably about 250° F., are suitable.

It may be desirable to supply additional aluminum chloride in the form of a hydrocarbon complex or as a slurry from an outside source (not shown). The aluminum chloride solution can be prepared as previously described from the fresh naphtha feed and introduced in a separate stream through line 52.

20 The introduction of make-up catalyst in the form of a solution is a distinct advance over the prior art. By this means it is possible to obtain an even and regulated flow of make-up aluminum chloride to the reaction system so that the complex is formed in situ and can be adjusted according to the amount of catalyst necessarily withdrawn. Moreover, the introduction is smooth and easy with no plugging of lines and no settling out of catalyst as is often the case when a slurry type addition is employed. More intimate mixing is possible by the use of a solution of aluminum chloride than is possible by the use of a slurry and even by the use of a preformed complex since there is no stratification within the reactor or in the lines and turbulence is only necessary in order to insure intimate contact between the reactants and the catalyst.

35 40 45 50 55 55 There is an added advantage to the use of butane as a solvent for the introduction of catalyst apart from the fact that much larger quantities of aluminum chloride can be dissolved and that is the fact that higher temperatures, particularly temperatures upwards of 350° F. can be safely used without excess degradation of the charging stock to light gases. The butane apparently acts as a "buffer gas" and prevents or minimizes the production of additional quantities of gaseous hydrocarbons such as are generally formed at the higher temperatures above recited. This advantage is even more pronounced if a feed stock containing heptanes and higher paraffins is used.

60 65 70 75 Although we have directed our description to a process involving the isomerization of a light naphtha fraction it is possible to use this system for the isomerization of normal butane to isobutane with no light naphtha present. Sufficient make-up catalyst may be dissolved in the incoming butane feed to supply the needs of the reaction. Obviously, variations in temperature and pressure from those described would be required and it is usually desirable to carry out butane isomerization in the absence of hydrogen or at least under very low hydrogen pressures.

Although we have described our process with reference to one preferred embodiment thereof, it should be realized that this is by way of illustration and not by way of limitation and that our invention is limited only as set forth in the appended claims. We have also omitted various details the necessity for which would be obvious

to one skilled in the art wishing to practice our invention.

We claim:

1. In a process for isomerizing paraffin hydrocarbons of the butane to hexane boiling range by means of a liquid aluminum chloride-hydrocarbon complex catalyst wherein the activity of the catalyst in a reaction zone is maintained by the addition of make-up aluminum chloride thereto, the method of operation which comprises maintaining a mass of aluminum chloride-hydrocarbon complex in said reaction zone up to a high level which is spaced from the top of said zone, heating a portion of a charging stock consisting chiefly of paraffin hydrocarbons of the butane to hexane boiling range in the absence of hydrogen chloride to a temperature within the approximate range of 200° to 300° F. and passing the heated portion through a mass of solid aluminum chloride for dissolving a regulated amount of aluminum chloride, absorbing hydrogen chloride in another portion of said charging stock and heating said other portion to an isomerization temperature below 300° F., introducing both portions of said charging stock into said mass of complex catalyst and passing said charging stock upwardly through said mass under isomerization conditions at a temperature below 300° F., separating hydrocarbons from complex in the upper part of said zone, removing hydrocarbons from said zone at a point above the level of the complex mass of catalyst therein, separating catalyst material and hydrogen chloride from the removed hydrocarbons, recycling separated hydrogen chloride without contacting it with said solid aluminum chloride, and introducing an amount of aluminum chloride by said solution step to provide an over-all make-up of more than .1 but less than 4 pounds of aluminum chloride per barrel of stock charged.

2. An isomerization process which comprises preparing a paraffinic hydrocarbon charging stock of the butane to hexane boiling range which contains substantially no olefins, less than

5% of aromatics and less than 10% of hydrocarbons higher boiling than normal hexane, heating one portion of said charging stock in the absence of hydrogen chloride to a temperature within the approximate range of 200° F. to 300° F. and passing said heated portion through a mass of solid aluminum chloride for dissolving a controlled amount of aluminum chloride, absorbing in another portion of the charging stock 10 an amount of hydrogen chloride within the approximate range of 2 to 10% by weight based on total stock charged and effecting said absorption in said other portion of the charging stock before said other portion is heated, subsequently 15 heating said other portion of the charging stock containing absorbed hydrogen chloride to an isomerization temperature but below 300° F., introducing both portions into a deep body of liquid aluminum chloride-hydrocarbon catalyst complex in a conversion zone, passing said charging stock upwardly through said body of complex under isomerization conditions at a temperature below 300° F., separating hydrocarbons from complex in the upper part of said zone, removing 20 hydrocarbons from the upper part of said zone at a point above the top of the body of complex therein, separating catalyst material and hydrogen chloride from the removed hydrocarbons, recycling separated hydrogen chloride to said absorbing step, and introducing an amount of aluminum chloride by said solution step to provide an over-all make-up of more than .1 but less than 4 pounds of aluminum chloride per barrel of stock charged.

35 3. The method of claim 1 wherein the portion of the charging stock contacted with solid aluminum chloride consists essentially of butane.

4. The method of claim 2 wherein the portion of the charging stock in which hydrogen chloride is absorbed consists essentially of hydrocarbons of the pentane-hexane boiling range.
